BY Victor J. Evans

ATTORNEY

WITNESS:

Patented Apr. 6, 1926.

1,580,034

UNITED STATES PATENT OFFICE.

CARMELINO GULFI, OF BOSTON, MASSACHUSETTS.

CUE.

Application filed November 18, 1925. Serial No. 69,899.

To all whom it may concern:

Be it known that I, CARMELINO GULFI, a citizen of the United States, residing at Boston, in the county of Suffolk and State 5 of Massachusetts, have invented new and useful Improvements in Cues, of which the following is a specification.

This invention relates to improvements in tips for use upon cue sticks contemplating the provision of means for removably securing the tip upon the cue whereby new tips may be substituted for old ones when the latter becomes broken or hardened.

With the above and other objects in view, 15 the invention further includes the following novel features and details of construction, to be hereinafter more fully described, illustrated in the accompanying drawings and pointed out in the appended claims.

20 In the drawings:—

Figure 1 is a fragmentary elevation of my invention after completed and in use.

Figure 2 is a fragmentary longitudinal sectional view taken through the forward 25 end of the cue stick and illustrating the manner in which my invention is applied thereto.

Figures 3, 4 and 5 illustrate various sections and elevations of the parts so forming my invention.

30 Referring to the drawings in detail, wherein like characters of reference denote corresponding parts, the reference character 10 indicates the end portion of a cue stick, not shown, which being of the usual 35 and well known construction and forming no part of the present applicant for Letters Patent but being merely shown for purposes of illustration in bringing forth the novel advantages of the above entitled invention.

40 The invention resides in the provision of a reduced extension or dowel 11 having a threaded bowl 12 extending inwardly from its end an appreciable distance. Receiving 45 the dowel 11 within a relatively large socketed portion 13 and having a relatively large bore 14 registering with the threaded bore 12 thereof is a barrel 15 being so configurated as to resemble an 50 integrally formed end of the cue stick end 10. Threaded within the threaded bore 12 of the dowel 11 is a threaded shank 16 extending from the inner end of a shaft 17 being received within the relatively large bore 14 of the barrel 15 while a threaded socket 18 provided in the opposite end of the

shaft 17 receives a threaded shank 19 provided upon the inner end of a cup-shaped plate 20 having forwardly extending teeth 21 provided upon the periphery thereof. 60 A tip 22 of the usual and conventional form is then placed upon the cup-shaped member 20 and receiving the teeth 21 therein after which the said tip 22 is struck in order that the teeth may be bent outwardly in the manner as clearly illustrated in Figure 2 of the drawing whereby the tip 22 will be rigidly secured and held against accidental displacement. 65

It will thus be noted from the foregoing 70 description and accompanying drawing that this invention provides an unusual and advantageous form of securing means for cue tips in so far as all parts are interchangeable whereby tips may be replaced when 75 necessary and owing to the manner in which the dowel 11 and barrel 15 are associated the dowel 11 and cue stick end 10 are prevented from splitting, the said barrel having a configuration conforming to the cue stick 80 end 10.

The invention is susceptible of various 85 changes in its form, proportions and minor details of construction, and the right is herein reserved to make such changes as properly fall within the scope of the appended claims.

Having thus described my invention, what is claimed is:—

1. A cue stick of the character described 90 having a reduced dowel provided upon its forward end and including a centrally disposed longitudinally extending threaded bore provided within the forward end, a barrel having an enlarged socket for receiving the dowel therein and enlarged bore 95 communicating therewith for registering with the threaded bore of the dowel, a shaft having a threaded shank provided upon its inner end and received within the threaded bore of the dowel and providing a threaded socket within its forward end, and means fitted within the socket of the shaft for securing a cue tip upon the forward end of the 100 barrel. 105

2. A cue of the character described having a reduced dowel provided upon its forward end and having a centrally disposed longitudinal extending threaded bore provided within its forward end, a barrel having an 110 enlarged socket and bore associated therewith receiving the dowel within the socket

and having its bore registering with the threaded bore of the dowel, a shaft having an inwardly extending dowel shank received within the threaded bore of the dowel and 5 providing a threaded socket upon its forward end, and a threaded shank fitted with the threaded socket of the shaft and pro-

viding a cup-shaped member having outwardly and forwardly extending teeth projecting from the periphery thereof for securing a cue tip thereto.

In testimony whereof I affix my signature.

CARMELINO GULFI. 5
